(57) **CLAIM**

The ornamental design for a mower body, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a mower body, according to the present invention;

FIG. 2 is a front elevational view of the mower body of FIG. 1;

FIG. 3 is a rear elevational view of the mower body of FIG. 1;

FIG. 4 is a left side elevational view of the mower body of FIG. 1;

FIG. 5 is a right side elevational view of the mower body of FIG. 1;

FIG. 6 is a top plan view of the mower body of FIG. 1; and, FIG. 7 is a bottom plan view of the mower body of FIG. 1. The dashed lines in the Figures are for environmental purposes only and do not form a part of the claimed design.

1 Claim, 5 Drawing Sheets
